UNITED STATES PATENT OFFICE

SHAUBUT C. WALZ, OF UPPER MONTCLAIR, NEW JERSEY, AND WILLIAM A. ADAMS, OF NEW YORK, N. Y.

DESIGN FOR A BADGE

Application filed January 13, 1933. Serial No. 46,822. Term of patent 3½ years.

To all whom it may concern:

Be it known that we, SHAUBUT C. WALZ and WILLIAM A. ADAMS, both citizens of the United States, and residents of Upper Montclair, in the county of Essex and State of New Jersey, and New York, in the county of New York and State of New York, respectively, have invented a new, original, and ornamental Design for a Badge, of which the following is a specification, reference being had to the accompanying drawing, forming part thereof.

We claim:

The ornamental design for a badge, as shown.

SHAUBUT C. WALZ.
WILLIAM A. ADAMS.
